UNITED STATES PATENT OFFICE

THOMAS OLIVER OTT, OF COLUMBUS, GEORGIA, ASSIGNOR TO CENTENNIAL COTTON GIN CO., OF COLUMBUS, GEORGIA, A CORPORATION OF GEORGIA

YIELDING MOUNTING FOR PICKER ROLLS

Application filed August 11, 1930. Serial No. 474,519.

The present invention relates to cotton ginning machinery and particularly to a gin having an automatic discharge picker roll.

An object of the invention is to provide a special yielding mounting for the picker roller so that when any obstructing material arrives between the picker roller and the cooperating saws and ribs, the picker roller will, by the obstruction itself, be caused to yield or 10 spring backward, permitting the obstruction to pass and thereafter return to its normal position in predetermined relation to its associated saws and ribs.

Another object of the invention is to provide such a picker roller mounting that is readily adjustable both vertically and horizontally and which is provided with quickly operable devices for adjusting the picker roll with respect to its proximity to the associated saws and ribs.

Other objects and advantages of the invention will appear from the following description, taken in connection with the accompanying drawings, which illustrate a preferred embodiment of the invention, and in which:

Fig. 1 is a fragmentary end elevation of a huller gin embodying the automatic discharge picker roll constructed in accordance 30 with the present invention;

Fig. 2 is a vertical sectional view taken on the line 2—2 of Fig. 1;

Fig. 3 is a horizontal sectional view taken on the line 3—3 of Fig. 1;

Fig. 4 is a vertical sectional view taken on the line 4—4 of Fig. 1.

Referring in detail to the accompanying drawings, a movable front cover plate 11 of a huller gin is pivoted at 12 and swings relative to the side plates 13 which carry the picker roll mounting and associated mechanism of the present invention.

A picker roll 15 is carried by a shaft 16, which is mounted in an antifriction bearing 18. The bearing 18 is carried in a bearing housing plate 20. The plate 20 in the present embodiment is substantially T-shaped, as indicated in Fig. 1, and is adjustably carried by a swinging arm 21 pivotally mounted for 50 rocking movement on a stub shaft 22, which

is fixed to the outer face of the end plate 13. The bearing plate 20 is adjustably fastened to the swinging arm 21 by a pair of bolts 24 and 25, which are threaded into the arm 21 and have their shanks passing through vertically extending slots 27 in the bearing plate 20. Loosening of the bolts 24 and 25 thus permits the raising or lowering of the bearing plate 20 with respect to the swinging arm 21 and consequently effects a vertical adjustment 55 of the picker roll 15 with respect to its cooperating saws 29. At its lower end the bearing plate 20 has an inwardly extending projection 30, which is vertically threaded for the reception of a limiting stop bolt 31, which is provided with a lock nut 32 for maintaining the desired length of its shank extending upwardly from the projection 30, the stop bolt 31 being adapted to bear against a bottom edge of the arm 21, thus limiting the amount 60 of upward movement of the bearing plate 20 with respect to the swinging arm 21 and consequently limiting the amount of vertical adjustment of the picker roll 15.

The invention provides yieldable means for maintaining the picker roll and saws in predetermined horizontal relation to each other, but in such a manner that this relation changes and the picker roll moves when an obstruction is encountered, to permit the obstruction to pass through, after which the picker roll returns to its normal or predetermined horizontal relation to the cooperating saws.

In the present embodiment of the invention, a slotted opening 36 is provided near the lower end of the swinging arm 21 for the reception of one end of an adjusting rod 37, which has limited rocking movement in the slot about the pivot pin 39. The other end of the adjusting rod 37 is threaded and passes through a slotted unthreaded opening formed in a lower lateral extension 42 of the side plate 13. Beyond this extension an adjusting rod operating handle member 43 is in threaded engagement with the outer end of the adjusting rod 37. Encircling the adjusting rod 37 between the relatively fixed extension 42 and the relatively movable slotted portion 36 of swinging arm 21 is a coiled 85 90 95 100

compression spring 44, the effect of which is to urge the lower end of swinging arm 21 about its pivot 22 in a counterclockwise direction, as viewed in Fig. 1, to the limit permitted by the handle member 43, which prevents further movement of the adjusting rod 37 by contacting with the fixed extension 42. The distance which the coil spring can move the arm 21 and consequently the normal predetermined distance of the picker roll from the saws are thus both determined by the position of the handle member 43 on adjusting rod 37. Rotation of the handle member 43 outward on its adjusting rod permits the spring to move the picker roll nearer the saws, and rotation of the handle member 43 inward of the adjusting rod moves the picker roll further away from the saws. Due to the yielding mounting of the picker roll, as above described, any obstruction between the picker roll and saws, since the saws are mounted to rotate about a fixed axis, will force the picker roll mounting assembly towards the left, as viewed in Fig. 1, to permit the obstruction to pass through, and after the picker roll has been moved for this purpose and the obstruction has passed, the picker roll immediately returns to its former position predetermined by the position of the handle member 43 on the adjusting rod 37.

The invention also provides means whereby the swinging front is shifted and adjusted whenever the position of the picker roll is shifted and whereby any operating parts mounted on the swinging front and cooperating with the picker roll will be likewise shifted and maintained in relative position to the picker roll. In the present embodiment this means includes a slide 50 both ends of which are turned at right angles to the main body of the slide as shown in Fig. 3. The slide 50 is provided with a slot 51, through which two guide pins 53 extend, their ends being threaded in the plate 13. These pins hold the slide 50 loosely enough to permit it to be moved back and forth in the direction of its slot with respect to the fixed plate 13. The inner end 55 of the slide is adapted to be contacted by a vertical edge of the arm 21, as shown in Figs. 1 and 3, and the outer end 56 of the slide is adapted to abut against the inner face of the swinging front plate 11, as shown in Fig. 1.

When the picker roll assembly is moved to the left against the action of spring 44, as viewed in Fig. 1, due to an obstruction as already described, the swinging arm 21 moves the slide 50 to the left, thus causing the outer end 56 of the slide to encounter the inner face of the swinging front plate 11, moving it outwardly about its pivot 12. Thus it is that the swinging front is shifted and adjusted whenever the position of the picker roll is shifted and therefore any operating parts mounted on the swinging front

and cooperating with the picker roll will likewise be shifted and maintained in a relative position to the picker roll.

The plate 21 is slotted, as indicated at 57, to permit adjustment of the picker roll shaft 13 with respect to the arm 21, and a corresponding opening 58 is provided in the plate 13 for the same purpose. Swinging movement of the arm 21 is limited by a bolt 59, which passes through a curved slot 60 in the arm 21 and has its inner end threaded into the fixed plate 13.

What is claimed is:

1. A huller gin having a picker roll and cooperating saws, movable picker roll bearing supporting arms, bearings for said picker roll carried by said arms, and devices holding said arms yieldingly in predetermined position with respect to said saws. 80

2. A huller gin having a picker roll and cooperating saws, pivoted picker roll bearing supporting arms, bearings for said picker roll carried by said arms and movable thereon, and devices holding said arms yieldingly in predetermined position with respect to 90 said saws. 90

3. A huller gin having a picker roll, cooperating saws, pivoted picker roll bearing supporting arms, bearings for said picker roll carried by said arms and vertically movable thereon, and devices holding said arms yieldingly in predetermined position with respect to said saws, said devices including adjusting rods and springs cooperating with 100 said arms. 95

4. A huller gin having a picker roll, cooperating saws, head plates, picker roll bearing supporting arms pivotally mounted thereon, bearings for said picker roll carried by said arms and vertically movable thereon, and devices holding said arms yieldingly in predetermined position with respect to said saws, said devices including adjusting rods cooperating with said arms and provided with handle operating means cooperating with said head plates for moving said arms away from said saws, and a spring encircling each adjusting rod and cooperating with said arms and said head plates for urging said arms yieldingly toward said saws to a position determined by said handle operating means. 110

5. A huller gin having a picker roll, cooperating saws, head plates, bearing supports for said picker roll, and devices for holding said bearing supports yieldingly in predetermined position with respect to said saws, said devices including springs urging said bearing supports toward said saws, and adjusting members cooperating with said supports and said head plates and adjustably limiting the movement by said springs of said supports toward said saws. 120

6. A huller gin having end head plates and a movable front plate, a picker roll and co- 130

operating saws, bearings for said picker roll, and devices holding said bearings yieldingly in normal predetermined position with respect to said saws, said bearings being movable away from said saws by an obstruction between the saws and picker roll and being returned to said predetermined position by said devices after such obstruction has passed, and front plate opening members actuated by movement of said picker roll bearings away from said saws for moving said front plate outwardly with respect to the gin to discharge obstructions therefrom.
